CLAIM

The ornamental design for anesthetic bottle piercer, as shown and described.

DESCRIPTION

FIG. 1 is a front perspective view of an anesthetic bottle piercer showing my new design;

FIG. 2 is a top plan view;

FIG. 3 is a rear elevation of the anesthetic bottle piercer; FIG. 4 is a side elevation taken from the left-hand side of the view illustrated in FIG. 1;

FIG. 5 is a side elevation of the side opposite that illustrated in FIG. 4;

FIG. 6 is a bottom plan view;

FIG. 7 is a front perspective view of a second embodiment of an anesthetic bottle piercer showing my new design;

FIG. 8 is a top plan view thereof;

FIG. 9 is a rear elevational view thereof;

FIG. 10 is a side elevational view thereof;

FIG. 11 is a side elevational view thereof, opposite that shown in FIG. 10; and,

FIG. 12 is a bottom plan view thereof.

The broken line showing of the support in FIGS. 1, 2, 4 through 8, and 10 through 12 is for illustrative purposes only and forms no part of the claimed design.
